UNITED STATES PATENT OFFICE.

JOHN C. MILLER, OF CANTON, OHIO, ASSIGNOR TO THE MILLER PASTEURIZING MACHINE COMPANY, OF CANTON, OHIO, A CORPORATION OF OHIO.

APPARATUS FOR FILLING AND CAPPING BOTTLES.

1,225,349.

Specification of Letters Patent.

Patented May 8, 1917.

Application filed August 24, 1903. Serial No. 170,645.

To all whom it may concern:

Be it known that I, JOHN C. MILLER, a citizen of the United States, residing at Canton, in the county of Stark and State of Ohio, have invented certain new and useful Improvements in Apparatus for Filling and Capping Bottles, of which the following is a specification, reference being had therein to the accompanying drawing.

10 This invention relates to apparatus for automatically filling bottles with liquid and then automatically capping them.

One of its objects is to provide a machine adapted for use where large quantities of 15 milk or other liquid are placed upon the market in bottles. The machine is so constructed and arranged that it may be speedily and efficiently adjusted to fill a bottle or bottles of different capacities, such as pints 20 and quarts, with liquid.

It has further for its object to reduce the labor incident to filling and capping of bottles to a minimum.

With these and other objects in view, the 25 invention consists of the parts and combinations of parts hereinafter described and set forth in the appended claims.

For the purpose of illustration I have, in the accompanying drawings, shown and 30 herein described one form of apparatus embodying my invention.

Figure 1 shows a mechanism embodying my invention in perspective.

Fig. 2 is a vertical longitudinal central 30 section of the mechanism.

Fig. 3 is an elevation of the filling end of the mechanism.

Fig. 4 shows partly in section and partly in elevation a portion of the capping devices 40 at the time of insertion of the cap in the bottle.

Fig. 5 shows partly in section and partly in elevation a portion of the capping devices in initial position above the bottles.

45 Fig. 6 is a plan view of parts of the cap feeding mechanism showing the valve plate in full lines at one end of its stroke and in dotted lines at the other end of its stroke.

Fig. 7 is a sectional view showing the filling plunger and valve, showing its position 50 within the bottle at the time of delivering the liquid.

Fig. 8 is a sectional view of the same parts

shown in view 7 with the plunger in initial position above the bottle.

Fig. 9 is a detail of the driving mechanism for the conveyer.

Fig. 10 is a detail of the conveyer driving devices.

Fig. 11 is a detail of the main driving 60 mechanism.

Figs. 12 to 15 show additional details.

In the drawings A represents the framework as a whole, B the conveyer for the bottles, C the liquid receptacle or tank, D the filling devices as an entirety, E the capping devices as an entirety and F the sealing mechanism as an entirety. The main or primary driving mechanism is indicated by G and the driving mechanism for the conveyer and for the stop devices by H, while I designates the mechanism for regulating the feed of the liquid as a whole.

The frame A preferably consists of a metal base 1 upon which are secured the side plates 2. 3 is a box like receptacle secured between the side plates and supported by them and by the bracket 4 which is also secured to the side plates. At the rear said side plates are joined by a T-shaped member 5 which serves also as a bracket upon which to mount some of the driving parts, as will be hereinafter described. To the lower front end of the box like receptacle 3 is secured a plate 6 having as many bosses or 75 projections 7 as the machine has filling ducts. 8 indicates bolts by means of which this plate is secured to the receptacle 3. At its ends the bar or plate 6 is provided with projections or bosses 9 in which are rigidly secured the guide rods 10 for the plunger system. 11 is a tank of any suitable material adapted to fit into the receptacle 3 and to receive the charge of liquid to be bottled. Through the bottom of this liquid tank 90 near its front end and central of the bosses of the plate 6 and extending therethrough and through the bottom plate of the receptacle 3 are arranged the liquid escape ducts 12. Fitted into the bosses 7 are the tubes 100 13 for directing the liquid to the bottles. To each of these tubes is fitted a sleeve 14 which at its lower end is enlarged as shown at 15. This enlargement or head 15 has an annular groove 16 adapted to receive the 105 mouth of a bottle and is flared, as shown at

17, to direct the mouth of the bottle into the groove. This head is also provided with an annular, inwardly projecting shoulder 18 beveled, as indicated at 19, to provide a seat 5 for the liquid release valve. 20 is a packing ring screwed into the top of the sleeve and fitting the tube 13 sufficiently snugly to prevent the escape of liquid between said tube and the sleeve 14. A rubber gasket, not 10 shown, may be inserted in the groove 16 to prevent excessive pressure between the bottle and the head 15.

The liquid releasing mechanism consists of a valve 21. It may be made of any suitable material, but preferably of rubber. As 15 shown, it has a smaller end 22 adapted to pass up into the head 15, a beveled shoulder 23 adapted to contact with the shoulder 18, of said head and to seal the liquid passage 20 therethrough and a large end or nose 22' adapted to engage a bottle mouth to center it. The nose 22' of the valve is preferably rounded. The valve rods 24 extend up through the liquid escape ducts 12 and upward through tank 11, and are secured to the cross head 25 in any suitable manner, preferably by a connection, preferably comprising screw threads and a lock nut, as shown at 24*. This cross head is provided 25 at its ends with shoulders or bosses 26 through which the rods 10 are passed, said rods serving to guide the cross head and to maintain all the operative parts connected therewith in proper fixed relations as the 30 said cross head is raised and lowered. 28 are anti-friction rollers mounted at either side of said cross head for a purpose to be hereinafter described.

31, 31, are rods slidably mounted at their 40 upper ends preferably in brackets 29, each of which is secured to a projection 30 on the cross head 25. The rods 31 at their lower ends carry the depression plates 32 for the sleeves 14. Said plates 32 are secured to 45 the rods 31 between two adjustable collars 33 which are adapted to be locked to the rods by the set screws 34. 36 is a loose collar mounted on each rod 31 above the upper collar 33. The collar 36 serves as an abutment for a spring 37 which surrounds the adjacent rod 31. Each spring 37 extends 50 between said collar 36 and the adjacent bracket 29 and tends to move the adjacent plate 32 downwardly.

55 The depression plates 32 bear upon sleeves 14 and are adapted to cause them to move downward, as will be hereinafter described. 38 is a lever arm pivotally mounted on the shaft 39 which is mounted in bracket 4. It 60 is provided at 40 with a longitudinally adjustable weight and at 41 with a widened and bifurcated end. The end 41 of each arm is adapted to partially surround the adjacent sleeve 14 and to bear upon the depression plate 32.

The capping devices are arranged near the opposite end of the machine from the filling devices. 42-43 are guide sleeves secured to the frame and adapted to guide the slide rods 44 which are mounted to move longitudinally therein. 45 is a cross head 70 secured to the rods 44 by the bolts 46 and adapted to move up and down with said rods.

47 are plungers movably mounted in vertical legs of the brackets 4. There are, by preference, as many plungers 47 as there are filling heads 14, and each plunger is arranged in the longitudinal plane of a filling head. The plungers are preferably hollow, 75 as shown at 51, to form a tube-like member. In the drawings, for illustration, I have shown a plunger in which 48 is a rod one end of which is secured in a well known manner to the cross head 45 and the other 80 end is provided with an enlargement or piston 49 adapted to engage with a spring 50 in the interior of the tube 51. This tube is preferably of a diameter slightly less than the diameter of the bottle stopper or disk 90 and is preferably closed at both ends as shown. 52' is a needle point secured in the lower end of the tube 51 and serves to penetrate and guide the closure or disk. Rigidly secured in the horizontal legs of the brackets 95 4 are the feed hoppers or magazines 52 for the closures or disks equally spaced from the plungers. Said hoppers 52 pass up through and loosely fit suitable openings in the cross head 45 as shown, and are adapted 100 to hold disks 53. 54 is a weight rod of any suitable size and shape adapted to bear upon and cause the downward feed of the disks in the magazine. 55 represents a longitudinal slot in the magazine wall, which enables 105 the operator to readily see the height of the pile of disks therein.

56 are shoulders or lugs on the bracket 4 which project out under the magazines 52. Upon said shoulders and in close proximity 110 to the bottom of the said magazines is secured a plate 57 extending from one side of the machine to the other, and provided at 58 with apertures adapted to register with the grooves in the mouths of the bottles to be 115 capped. Mounted on said plate 57 is the endwise movable valve plate or disk advancing plate 59. It is maintained in position by the guide strips 60 secured to the said plate 57. This valve plate 59 is provided with disk or closure receiving apertures 61 so spaced as to register with the lower orifice of the magazines and receive a disk when the bottles are being advanced to the capping point, and to register with the 120 apertures 58 in the plate 57 and deliver the aforesaid disk thereto prior to the descent of the plungers. 62 are spring controlled wings or clips pivoted at 63 in grooves in the under side of the plate 57, and adapted 130

to normally obstruct the passage ways or apertures 58. 64 are torsion springs mounted on the pivots 63 and adapted to hold the wings normally across the mouths 5 of said apertures. 65 is an opening in one side of the frame to permit the endwise movement of the valve plate 59.

The bottle advancing or conveying mechanism consists of a table 66 provided at each 10 end with a pair of downward projections 67 having enlarged bearings 68. In these bearings are rotatably mounted the shafts 69, 70 at front and rear ends of the machine, respectively. 71 represent sprocket wheels 15 secured to said shafts 69, 70 and adapted to engage and drive the conveyer 72. This conveyer is of peculiar and novel construction. As illustrated, it consists of a series of parallel cross carriers 73 connected together by links 74, each cross carrier having 20 distinct and separate receiving compartments for as many bottles as the machine is adapted to fill at one time. Each cross carrier consists preferably of a bar 75 recessed as indicated at 76 for the purpose of lightening 25 the parts. 77 are spring controlled jaws, one for each bottle, supported at each end by pins 78 seated and secured in the bars 75, the heads 79 of the pins limiting the outward movement of the jaws 77 relative to 30 said bar. 80 are springs mounted in adjacent recesses in the said jaws and in the bar 75 and adapted to afford a yielding grip for the bottles to be advanced.

35 81 are parallel ribs arranged longitudinally of the table and preferably secured thereto by the bolts 82. They lie below the carrier bars which travel longitudinally over them and serve to separate and brace the 40 bottles at their bottoms.

Motion is imparted to the conveyer 72 through the shaft 83 mounted in bearings 84 (see Fig. 9) in the downward projections 45 85 of the table. The transmission of power is obtained through a wheel 86 secured to said shaft and provided near its periphery with a lug 87 projecting at right angles to its face, said lug being adapted to engage with the radially arranged clips 88 on the 50 face of a wheel 89 rigidly secured to the shaft 70. By these devices a step by step motion is imparted to the conveyer, the movements depending on the rotation of the shaft 83 to insure that the bottles shall be 55 positioned properly at the points where they are to be filled and capped.

I provide automatically actuated stop devices for each of the bottles adapted to limit the advance of the same beyond a certain 60 point during each step by step movement of the conveyer. The parts of these stop devices are illustrated in Fig. 2. 90, 91 are horizontal cross bars arranged beneath the table 66. Secured thereto and extending vertically upward therefrom are the pins of

stop bars 92, 93, which pass through the bosses or guides 94 on the table and are adapted to be projected into the path ways of the bottles at their points of filling and capping, as shown. 95, 96, are brackets secured to the bottom of the table and adapted to support the cross bars 90, 91, and their operative parts. 97 is a longitudinally reciprocating rod fitted into the guides 98 on the said brackets and adapted for slight vertical play therein. At its front end the said rod is pivoted to one arm of a bell crank lever 99 which is pivotally mounted in a projection on the bracket 95. The other arm of said lever is pivoted to one end 70 75 of the link 100 the opposite end of which is pivoted to a lug 101 on the bar 90.

At its rear end the rod 97 is pivotally connected to one arm of a bell crank lever 102 which is likewise pivotally mounted in a 80 projection on the bracket 96 and the other arm of which is pivotally connected to one end of a link 103 the opposite end of which is likewise pivoted to a lug on the bar 91. It will be noted that the bell crank levers are 85 mounted in such a manner that the weight of the parts supported by them will tend normally to throw the rod 97 rearward and withdraw the stop bars 92, 93, from the path 90 of the bottles.

95 104 is a cam secured to the shaft 83. Its edges engage with the rear end of rod 97 and are constructed and timed to cause the gradual forward movement thereon of the rod 97 so that the stop bars 92, 93, will be 100 projected into the paths of the bottles as they approach the filling and capping points, and the cam will, furthermore, permit the gradual withdrawal of said stop bars on the return throw of the return rod 97.

105 It is very essential in machines of this description that quick and efficient means be provided for the adjustment of the bottle supports or table relative to the filling and capping parts or vice versa, so as to readily 110 accommodate the machine for the filling and capping of bottles of different lengths. For this purpose I have mounted and balanced the table centrally upon a support or bracket 115 105, free to be vertically adjusted relative to the filling and capping mechanisms. 106 are bolts for securing the table to the support 105. 108 is a vertically arranged shaft provided at its upper end with a screw threaded part 109 which is adapted to be 120 screwed into the body of the support. At the lower end of the screw there is a bearing plate and the lower end of the shaft carries the bevel gear 111. 112 is a cross plate secured at its ends to the sides of the base 1. 125 It serves as the supporting member for the table. The shaft 108 passes centrally through this plate and the hubs or bearing pieces 113, 114, are secured to either side thereof. The collar 110 bears upon the up- 130

per end of the hub 113. 115 is a horizontal shaft arranged directly below the vertical shaft 108 and having its ends mounted in the framework 1. It is provided with a bevel gear 116 adapted to mesh with and drive the bevel gear 111. The shaft 115 projects beyond one side of the base of the machine and is provided with a hand wheel 117 through which power may be applied to turn the shaft, thereby raising or lowering the table and its attached parts as desired.

118 is a paraffin tank supported on brackets 119 secured to the sides 2 of the frame, only one of said brackets being shown in the drawings (see Fig. 1). It is adapted to deliver melted paraffin to the top of the bottles after they have been capped, for the purpose of sealing them. 120 are apertures in the bottom of said tank for the purpose of permitting the escape therefrom of the paraffin to the tops of the bottles. 121 is an endwise reciprocating valve plate supported adjacent to the bottom of the tank by guides 122 which are secured to the bottom of said tank. This plate is provided with apertures 123 adapted to register at predetermined intervals with the apertures 120 in the bottom of the tank to permit the escape of a sufficient amount of paraffin to properly seal the bottle closures. 124 is a pipe for steam or hot water leading to the heating coil 125 in the bottom of the tank which is adapted to keep the paraffin in a molten condition. 126 is a discharge pipe for the water. Above each aperture in the tank may be arranged a throttle valve as indicated at 127, consisting preferably of a disk 128 with an aperture therethrough adapted to register with the aperture in the tank below it. This disk is provided with a stem 129 preferably swiveled thereto. The stem 129 extends through and by means of a screw thread adjustably engages with one side wall of the tank. The stem 129 may be provided at its outer end with a thumb piece 130. The flow of paraffin through any one or all of the apertures may thus be quickly regulated by adjusting said throttle valves.

The power for driving all the operative parts of the apparatus is applied through the pulleys 131 on the shaft 132 which is preferably mounted longitudinally of the machine in bearings 133, preferably formed integral with the cross plate or bracket 5. The shaft is provided between said bearings with a worm 134 adapted to mesh with and drive a worm gear 135 secured to the transverse shaft 136 which is rotatably mounted in bearings 137 on the upwardly extending arms 138 of the sides of the frame. Power for operating the filling and capping mechanism is applied as follows: At its extremities this transverse shaft 136 carries cranks or cam-like devices 139. The devices 139 preferably comprise disks provided with

crank lugs 140 projecting from their outer faces. The said lugs are adapted to engage with and operate the levers 141 which are pivotally fulcrumed on shafts 142 rigidly secured in bosses 143 projecting from the side plates of the frame. The other ends of said levers 141 engage with the anti-friction rollers or lugs 28 on the front cross head 25. A second pair of levers 144 are pivoted at their front ends to shafts 145 each rigidly secured in a boss 146 at the upper front corner of each side plate 2. Said levers 144 are connected to the levers 141 above them by means of pivoted links 147 and the rear ends of said levers 144 are connected between collars 148 to the slide rods 44 of the rear cross head 45.

149 is the cam through which motion is transmitted to the reciprocating valve plates 59 and 121. It is secured to the shaft 136 at any convenient point. 150 indicates the groove or guide on the periphery of said cam and 151 the lug or roller on the arm 152 which is adapted to operate in said groove or guide. The shaft 153 to one end of which the rocker arm 152 is rigidly secured, is mounted in a bearing plate 154 supported on top of the paraffin tank 118. To the other end of said shaft is connected a rod 155 carrying at its lower end plates 156, 157, which are adapted to be connected to the under sides of the valve plates 59 and 121 respectively; portions of the cross plate 57 and of the guide strips 122 on the bottom of the paraffin tank being cut away to permit the attachment of said plates 156 and 157 to their respective valve plates, and to provide for the reciprocations thereof.

In Fig. 11 is shown in plan view and in full and dotted lines the positions of extreme throw of the rocker arm 152.

The power transmitting devices for the conveyer comprise a gear 158 rigidly secured to the shaft 136 and adapted to mesh with a pinion 159 on a shaft 160 mounted in a bearing 161 at the upper end of the frame arm 138. On the outer end of the shaft 160 is secured a sprocket wheel 162 belted by a chain 163 to a sprocket wheel 164. The sprocket wheel 164 is secured to a counter shaft 165 which is mounted in a bearing 166 carried by the table 66. On the inner end of said shaft 165 is secured a gear 167 which meshes with a gear 168 on the shaft 83.

One of the chief difficulties experienced with automatic capping mechanisms for bottles results from the irregularities in shape of the mouths of the bottles and in all machines of this class it is essential that means be provided for centering the mouths of the bottles so that the inserting device for the closures will register exactly with the groove or opening in the mouths thereof. With this end in view I have provided a centering mechanism for the bottles which is indicated

as a whole by L. It consists of a transverse bar 169 secured in the side plates of the frame. Pivoted to said bar are a series of parallel arms or bars 170 arranged above the pathways of the bottles along the tables and each provided with a plate 171 having an aperture 172 slightly larger in diameter than the plunger 47.

The under surfaces of these plates surrounding said apertures are flared as indicated at 173 for the purpose of engaging the mouths of the bottles and directing their openings to register with the apertures 172, thus insuring that the closures will be properly directed into the mouths of the bottles. 174 is a transverse bar arranged above the arms 170 and to which said arms are preferably secured by screw rods 175. At its ends said bar is mounted on the rods 176 pivotally suspended from the levers 144 and guided at their lower ends in brackets 177 secured to the sides of the frame. Springs 178 mounted on the rods between the said brackets and the bar 174 exert an upward pressure on the bar, thus holding the centering arms normally above the bottles. 179 are collars rigidly secured to the rods 176 above the bar 174. Their function is to depress said bar against the pressure of the said springs as the lever 144 rocks downward, causing the centering arms to engage the mouths of the bottles and center them just prior to the insertion therein of the closure.

For the purposes of illustrating the complete operation of the machine it will be assumed that the conveyer sections above the table are supplied with a full complement of bottles 180; that is bottles in all stages of advancement from the point of insertion in the conveyer sections to the point of removal therefrom. Starting then with the front cross member 25 at the upper end of its stroke, as indicated in Figs. 1 and 3, the power is applied through the pulley 131 and transmitted through shaft 132 to the shaft 136 simultaneously imparting motion to all of the driven parts. The lugs 140 on the disks 139, which are at this time at the lowest points in their anti-clockwise paths of rotation, begin to rise thereby swinging the levers 141 on their pivots 142 and causing their front ends to descend and at the same time causing the descent of the levers 144 under pressure applied to them through the links 147, whereby the rear cross head 45 carrying the plungers 47 also begins its descent. As the front ends of the said levers 141 descend they are followed in their course by the cross head 25 under the force of gravity due to its own weight, the weights of the parts attached to it and the depression weights 40. The antifriction rollers 28 serving to minimize the friction between the levers 141 and the cross head 25. The power transmitted to the conveyer mechanism has

in the meantime caused the advance of the conveyer, and the projecting of the stop devices 92, 93 into the pathway of the bottles at the points of filling and capping, so that the bottles are now properly positioned under the respective devices. 70

The forward advance of the conveyer sections is then interrupted and the heads of the filling devices 15 engage with the mouths of the empty bottles, the collars 179 on the rod 176 contact with and depress the bar 174 and cause the centering arms 170 to engage and center the mouths of the bottles under the capping mechanisms. 75

The further downward movement of the forward ends of the levers 141 permits the cross head 25 carrying the valve rods 24 to unseat the escape valves 21 against the resistance of the springs 37 and thereby permit the flow of liquid from the tank 11 to the bottles. Just before the front ends of the levers 141 reach the lower end of their stroke the cam 149 operates the valve plates 59 and 121, the former transfers the closures or disks 53 from the magazines 52 to the apertures 58 above the bottles, depositing them upon the wings 62; while the valve plate 121 opens the escape ducts 120 to permit the flow of paraffin from its tank to the closures on the bottles beneath it. 80 85 90

The further downward movement of the levers 141, acting through the levers 144, causes the plungers 47 to drive the closures 53 into the grooves in the mouths of the bottles. By this time the lugs 140 have reached the uppermost point in their circular course and now begin to descend, thereby causing the outer ends of the levers 141 to swing upward carrying therewith the cross heads 25 and 45. 95

The cam 104 on the shaft 83 now permits the withdrawal of the stop elements 92, 93 from the paths of the bottles. The cam 149 shifts the valve plates 59 and 121 causing the apertures 61 in the former to register with the apertures in the magazines 52; the shifting of the latter valve cutting off the flow of paraffin from its tank. The escape valves 21 are reseated, cutting off the flow of liquid to the bottles and the filling heads 115 110 115 120 are lifted above the mouths of the same.

The lug 87 carried by the wheel 86 on the shaft 83 now engages with a cleat 88 on the wheel 89 and the conveyer moves forward advancing all the bottles one step. 120 In the meantime a row of bottles to be filled has been placed in the conveyer sections at the forward end of the table.

The quantity of liquid delivered to the bottles is governed by the diameter of the pulley 131 which determines the speed of rotation of the shaft 132. The driving pulley, not shown, being of fixed diameter and adapted to be rotated at a certain uniform speed the pulley 131 is so proportioned that 125 130

it will cause the valves 21 in the filling heads 15 to be unseated for a fixed period of time necessary to permit the flow of a predetermined quantity of liquid through 5 the tubes 13 into the bottles.

The machine shown in the drawings is adapted to supply bottles of two capacities. If the belt is placed upon the part of the pulley 131 of largest diameter the valve 21 10 will be opened for one period of time; on the other hand if the belt is placed upon the part of the pulley of smaller diameter, the operation of the parts of the machine will be more rapid than in the first instance, 15 and therefore a smaller quantity of liquid will be permitted to escape past the valve 21. It will thus be understood that by changing the speed of rotation of the shaft 132, the machine may be adapted to fill bottles of different capacity. 20

In many instances the sealing of the bottles may not be essential, in which case the paraffin tank and its operative parts may be omitted without interfering with the construction and operation of the rest of the machine.

When the table is adjusted vertically it is necessary that some form of compensating device be provided for either lengthening or 30 shortening the chain, according to the direction of adjustment of the table. In the drawings I have shown a slotted and grooved plate 181 secured to the framework of the machine. 182 is a bolt, the head of 35 which is adapted to engage with the inner walls of the said groove. This bolt extends outwardly from the frame and is provided with a tubing or sleeve 183 and a nut 184. A sprocket idler 185 is loosely mounted on 40 the said sleeve, as shown. When the table is raised or lowered, it is merely necessary to loosen the nut 184 and move the bolt 182 longitudinally of the stationary plate 181 until the idler gives the desired tautness in 45 the chain; then the bolt can be secured in position by tightening the nut.

When the filling heads 15 engage the mouths of the bottles they tend to form an air tight joint therewith and it is desirable 50 to provide an air vent for the escape of the air in the bottles during the filling thereof. To accomplish this the valve rods 24 are preferably hollow, as shown, and have near 55 their upper ends apertures 24' extending from the exterior of the rod to said hollow passage-way. It will be seen that the hollow valve rods provide communication between the interior of the bottles and the external air, and that the air in the bottles 60 can escape therefrom as the liquid rises therein.

The lower end of each valve is preferably rounded, as shown in Figs. 7 and 8. This end is arranged to project within the mouth

of a bottle and by engagement with the interior wall thereof to center it relative to the sleeve 14 in coöperative relation with the bell-shaped lower end thereof.

To those skilled in the art of making apparatus of the class described, many alterations in construction and widely differing embodiments and applications of my invention will suggest themselves, without departing from the spirit and scope thereof. My disclosures and the description herein 75 are purely illustrative and are not intended to be in any sense limiting.

What I claim is:—

1. In a machine of the class described, the combination of a frame, a liquid holder, 80 mechanism connected with said liquid holder for filling a plurality of bottles simultaneously, said mechanism including a plurality of ducts having valve seats and valves therefor, means for advancing rows 85 of bottles step by step and successively positioning the rows at the filling station with the mouth of each bottle of a row in alinement with one of said filling ducts, means for adjusting said bottle advancing 90 and positioning means relative to said filling mechanism, means for opening and closing said valves substantially simultaneously, and means for varying the period of time that 95 said valves are open.

2. In mechanism for filling bottles with liquid, the combination of power mechanism, a holder or receptacle for the liquid, a withdrawing duct communicating with the receptacle and having a downwardly movable 100 section, and a valve movable downwardly with and also relatively to said duct section to permit operation of the valve, and a conveyor for the bottles to be filled, said conveyor having its operative part adjustable 105 relatively to the movable section of the aforesaid duct.

3. In a machine of the class described, the combination of a liquid holding receptacle, means for supporting a bottle below said receptacle, a depending filling duct leading from said receptacle and comprising a stationary section connected thereto and a section slidable relative to said stationary section and arranged to engage with the mouth 110 of a bottle, a vertically movable frame, a valve mounted in the movable section of the filling duct for controlling the flow of liquid therethrough, and connections between the 115 stem of said valve and said frame for supporting and operating said valve.

4. In a machine for filling bottles with liquid, the combination of a frame, a holder or receptacle for the liquid, a duct leading from the liquid receptacle to a bottle and having a movable section, a weighted arm bearing against said movable section, power devices, and means actuated by the power 125

devices for moving the movable duct section relative to said holder or receptacle and in opposition to the weighted arm.

5. In a machine for filling bottles with liquid, the combination of a frame, a holder or receptacle for the liquid, a duct extending from the receptacle and having thereon a movable section, the lower free end of which engages with and closes the mouth of the

10 bottle, a valve adapted to engage the lower end of the movable section, a rod passing through the duct and connected to said valve, means for holding said movable section in engagement with the bottle, and

15 means for positively moving the valve through said valve rod independently of the movable section and relative to said holder or receptacle.

6. In a machine for filling bottles with liquid, the combination of a frame, a holder or receptacle for the liquid, a duct adapted

20 to conduct liquid from the receptacle to a bottle and having a movable section adapted to engage therewith, a gravity actuated bar

25 engaging with the movable section, a valve for closing the duct, a valve rod extending through the duct, and means for positively moving the valve rod and valve independently of the movable section.

30 7. In a bottle filling machine, the combination of a holder or receptacle for liquid, a bottle filling duct extending from said receptacle and having a movable section adapted

35 to engage the mouth of a bottle, a valve in said duct for controlling the flow of liquid therethrough, and automatically operated means for operating said valve relative to said holder or receptacle and for controlling the movement of said movable section to

40 ward and from the bottles.

8. In a bottle filling machine, the combination of a holder or receptacle for liquid, a filling duct extending from the said receptacle and having a movable section adapted

45 to engage the mouth of a bottle, a valve in said duct for controlling the flow of liquid therethrough, means for moving said movable section of the duct into engagement with the mouth of a bottle, and means for

50 operating said valve relative to said holder while the movable section of the duct is in engagement with the mouth of a bottle.

9. In a bottle filling machine, the combination of a supply tank, a filling duct ex-

55 tending from said tank and having a movable section adapted to engage the mouth of a bottle, a valve independently movable relatively to the movable section of the duct, and automatic means for operating the said

60 valve relative to said tank and for controlling the engagement and disengagement of the movable section with a bottle mouth.

10. In mechanism of the class described, the combination of a supply tank, means for

positioning a row of bottles at a filling station, a corresponding row of telescoping ducts, each connected with said tank at its upper end and arranged to engage a bottle mouth at its opposite end and having a valve seat, a valve for each of said valve seats disposed to enter the mouth of a bottle, and means for operating each valve relative to said tank.

11. In mechanism of the class described, the combination of a supply tank, means for 7 positioning a row of bottles at a filling station, a corresponding row of telescoping ducts, each connected with said tank at its upper end and arranged to engage a bottle at its opposite end and having a valve seat, 8 a valve for each of said valve seats, means for operating each valve relative to said tank, and compression means interposed between said ducts and valves tending to maintain the valve seat of each duct in engagement 85 with its valve.

12. In mechanism of the class described, the combination of a supply tank, means for positioning a row of bottles at a filling station, a corresponding row of valve stems, a 90 row of telescoping ducts through each of which a valve stem extends, each of said ducts being connected with said tank at its upper end and arranged to engage a bottle at its opposite end and having a valve seat, 95 a valve carried by each of said stems for the adjacent valve seat, each valve and stem serving to support the adjacent movable duct section, means acting on the movable section of each of said ducts for normally maintaining 100 its valve seat in engagement with the valve but permitting the movable section to telescopically move to open the valve when the duct engages a bottle mouth, and means for actuating said valve stem relative to said 105 tank.

13. In mechanism of the class described, the combination of means for positioning a bottle at a filling station, a supply tank formed with a liquid discharge opening, a 110 movable valve stem extending through said opening and provided with a valve at its lower end, a duct communicating with said discharge opening, a sleeve arranged to engage the mouth of a bottle and provided at its lower end with a valve seat for said valve, the said sleeve being slidable on the duct and supported by said valve, means acting on said sleeve to hold the valve seat thereof in engagement with the valve within predetermined limits of travel, and means for actuating said valve stem relative to said tank.

14. In mechanism of the class described, the combination of means for positioning a bottle at a filling station, a supply tank formed with a liquid discharge opening, a 115 valve stem provided at its lower end with a

valve having a rounded nose, a duct communicating with the discharge opening, a sleeve having at its lower free end a valve seat for said valve and a wall extending 5 from said valve seat, said sleeve being slidably mounted on said duct, and means acting on said sleeve normally to hold the valve seat thereof in engagement with the valve, said rounded nose on said valve and said 10 extending wall at the free end of said sleeve, being arranged to engage respectively the inner and outer walls of the mouth of the bottle and coöperating to center it, and said extending wall also serving to close the 15 mouth of said bottle during the operation of said valve.

15. In a machine of the class described, the combination of a bell-shaped element formed with an axially disposed passageway 20 through which liquid flows and with a valve seat, said bell-shaped element being adapted to engage the exterior of the mouth of a bottle to center and close it, a valve for said valve seat having an air duct through 25 it and a downwardly extending rounded nose, said rounded nose being adapted to engage the interior of the mouth of a bottle to center it, means for yieldingly holding said bell-shaped element in engagement 30 with the mouth of a bottle, and a valve stem extending through said bell-shaped element and having an air duct there-through communicating with the air duct through said valve.

35. 16. In a machine of the class described, the combination of a sleeve disposed at its lower free end to engage with and close the mouth of a bottle and having an axially disposed passageway for liquid and a valve 40 seat, a valve for said valve seat having an air duct through it and a downwardly extending rounded nose arranged to engage the mouth of a bottle and coöperable with the lower end of said sleeve to center the 45 bottle, means for yieldingly holding said sleeve in engagement with the mouth of the bottle, and a valve stem extending through said sleeve and having an air duct there-through communicating with said air duct 50 through said valve.

17. In a machine of the class described, the combination of a liquid receptacle, a row of ducts communicating therewith and depending therefrom, each duct comprising a 55 stationary section and a movable sleeve which telescopes it, means for positioning a row of bottles at the filling station, each of said sleeves being adapted to engage at its lower free end with the mouth of a bottle 60 and being capable of axial movement independently of the other sleeves in the row and having an axially disposed valve seat, a plurality of movable valves, one for each of said seats and each valve having an air duct 65 therethrough, a plurality of air vents, one

for each of said valves and each communicating at its lower end with the air duct through the valve to which it is connected, means for moving simultaneously said row of sleeves and plurality of air vents relative to said liquid receptacle when a row of bottles is positioned at the filling station, and means for holding each of said sleeves in engagement with the mouth of the bottle 70 engaged by it.

75 18. In a bottling machine, the combination with the frame, of a driving shaft, a supply tank, filling tubes, reciprocating sleeves yieldingly mounted upon said tubes, valves for said sleeves provided with tubular stems, and means for reciprocating said sleeves, said means consisting of a cross-head adapted to move vertically, connection between the cross-head and said valve stems, and gearing connecting the cross-head with 80 the said driving shaft.

85 19. In a bottling machine, the combination with the frame, of a supply tank, filling tubes opening into said tank, reciprocating sleeves slidably mounted upon said tubes, springs for said sleeves, valves situated in said sleeves and provided with tubular stems projecting axially through said tubes, a cross-head attached to said stems, and means for reciprocating said cross-head.

90 20. In a bottling machine, the combination with the frame, of a driving shaft, a supply tank, filling tubes communicating with said tank, spring held sleeves slidably 100 mounted upon said tubes, valves arranged in said tubes and having tubular stems projecting through the tubes, a cross-head attached to said stems, and means for reciprocating said cross-head, said means consisting of 105 members, rotating devices for operating said members and operative means connecting said rotating devices with the driving shaft.

110 21. In a bottling machine, the combination with the frame, of a supply tank, filling tubes opening into said tank, reciprocating sleeves slidably mounted upon said tubes, springs for said sleeves, valves situated in said sleeves and provided with tubular 115 stems projecting axially through said tubes, a cross-head attached to said stems, and means for reciprocating said cross-head, the said reciprocating means including a device which controls the opening of the valves in 120 said sleeves.

22. In mechanism of the class described, the combination of a receptacle, formed with a row of openings in its bottom, for holding liquid, ducts leading from said openings, 125 sleeves mounted on said ducts and arranged to move longitudinally thereof, each of said sleeves being formed with a valve seat, a cross-head, a row of rods secured to and depending from said cross-head, valves, one 130

for each rod, carried by the rods, and arranged to engage the valve seats of the sleeves, means acting on said sleeves to maintain their valve seats in engagement with the valves, and means for reciprocating said cross-head.

23. In mechanism of the class described, the combination of a receptacle, formed with a row of openings in its bottom, for holding liquid, ducts leading from said openings, sleeves mounted on said ducts and arranged to move longitudinally thereof, each of said sleeves being formed with a valve seat, a cross-head, a row of rods secured to and depending from said cross-head, valves, one for each rod, carried by the rods and arranged to engage the valve seats of the sleeves, springs acting on said sleeves to maintain their valve seats in engagement with the valves, and means for reciprocating said cross-head.

24. In mechanism of the class described, the combination of a receptacle, formed with a row of openings in its bottom, for holding liquid, ducts leading from said openings, sleeves mounted on said ducts and arranged to move longitudinally thereof, each of said sleeves being formed with a valve seat, a cross-head, a row of rods secured to and depending from said cross-head, valves, one for each rod, carried by the rods and arranged to engage the valve seats of the sleeves, means acting on said sleeves to maintain their valve seats in engagement with the valves, means for reciprocating said cross-heads, and means for advancing rows of bottles step by step to and from the filling station below said sleeves.

25. In a machine for filling bottles with liquid, the combination with a frame, of a holder or receptacle for liquid supported by the frame, a duct through which the liquid passes from said receptacle to a bottle, an intermittently moving carrier, movable stopping or arresting devices for the bottles, and intermittently acting devices for moving said stop devices into and out of the path of the bottles.

26. In a machine of the class described, the combination with a frame, of a holder for liquid supported thereby, filling ducts leading from said holder and adapted to engage the mouths of bottles, a carrier for advancing bottles step by step to and from said filling ducts, means for actuating said carrier step by step, means for adjusting said carrier vertically relative to said filling ducts, stop devices, adjustable with said carrier, movable into and out of the path of movement of the bottles to arrest them at a predetermined position, and means for controlling the movement of said stop devices.

27. In a bottle filling and capping machine, the combination of a frame, bottle conveying means, means for delivering caps

to the mouths of bottles, a receptacle for liquid supported on said frame, devices for controlling the flow of liquid from said receptacle, power devices for actuating the cap delivering means and the liquid control devices, and intermittently acting devices for stopping the bottles in proper position relative to the liquid filling devices and the cap delivering means independently of the conveying means.

28. In a machine of the class described, the combination with bottle filling and cap feeding and inserting mechanisms, of an endless bottle conveyer comprising two chains connected together by bars adapted to advance bottles horizontally in straight lines from the said filling mechanism to the said cap feeding and inserting mechanism, means for imparting a step-by-step movement to the said endless conveyer, stops arranged to project between the bars and engage the forward walls of the bottles for limiting the travel thereof relative to said filling mechanism and said cap feeding and inserting mechanism, and means for moving said stops into operative position.

29. In mechanism of the class described, the combination with bottle filling and cap inserting mechanism, of a bottle moving mechanism having cross bars adapted to advance bottles horizontally from said filling mechanism to said cap inserting mechanism, rising and falling stops arranged to project between the bars and engage the forward walls of the bottles to limit the travel thereof relative to the filling mechanism and the cap inserting mechanism, and means adapted to effect step-by-step movement of said bottle moving means and to actuate said rising and falling stops.

30. In a machine of the class described, the combination with a frame, of a receptacle for a liquid supported thereon, a conduit depending from said receptacle and adapted to convey the liquid to a bottle, mechanism for advancing and positioning bottles relative to said conduit, means for intermittently moving the said bottle advancing and positioning mechanism predetermined distances, devices for arresting the bottles, and means for moving said arresting devices into and out of the path of movement of the bottles.

31. In apparatus of the class described, the combination of a liquid receptacle, an intermittently operated bottle advancing mechanism arranged in a horizontal plane below said receptacle and adapted to move bottles relative thereto, filling ducts for conducting the liquid from the receptacle to the bottles, means for controlling the flow of liquid through said ducts, stops arranged to move into and out of the path of movement of the bottles for stopping them at a predetermined position, and means for op-

erating said stops at predetermined intervals relative to the movement of the bottle advancing mechanism.

32. In a mechanism of the class described, 5 the combination of a frame, mechanism for filling bottles, advancing means for moving the bottles to and from said filling mechanism, said means comprising a movable device and a table over which the bottles are 10 moved by said device, means for actuating the device step by step, and stops coöperating with said device actuating means, arranged to be projected through the table for stopping the bottles at a predetermined 15 position.

33. In mechanism of the class described, 20 the combination of a frame, mechanism for filling bottles, advancing means for moving the bottles to and from said filling mechanism, said means comprising a movable device and a table over which the bottles are moved by said device, means for actuating the device step by step, and vertically movable stops coöperating with said device actuating means and slidable in openings 25 formed in the table for stopping the bottles at a predetermined position.

34. In mechanism of the class described, 30 the combination of a frame, mechanism for filling bottles, advancing means for moving the bottles to and from said filling mechanism, said means comprising a movable device and a table over which the bottles are moved by said device, means for actuating 35 the device step by step, vertically movable stops coöperating with said device actuating means and slidable in openings formed in the table for stopping the bottles at a predetermined position, and means coacting 40 with the movable device actuating means for operating said stops at intervals.

35. In a machine of the class described, 45 the combination of means for filling a row of bottles with liquid, mechanism for advancing bottles to and from said filling means, the said advancing mechanism comprising a table provided with a series of longitudinally extending plates arranged parallel to each other and forming guideways through which the bottles move and a pair of chains connected together by transverse bars and arranged to slide on the upper edges of said plates, the said bars being arranged to engage the bottles and move 50 them longitudinally of said table, arresting devices arranged to project into the path of movement of said bottles but below the path of movement of said transverse bars to stop the bottles in registering position with said filling means, and means for operating said chains and arresting devices at intervals.

36. In a machine of the class described, 55 the combination of means for filling a series of bottles with liquid, a conveyer mecha-

nism for moving the bottles to and from said filling means, the said conveyer mechanism comprising a table provided with a series of longitudinally extending plates arranged parallel to each other and forming 70 guideways through which the bottles move, a series of connected together transverse bars arranged to slide on the upper edges of said plates to move the bottles longitudinally of the table, members carried by the bars and arranged to engage with the bottles and means for operating said transverse bars intermittently, arresting devices arranged to project into the path of movement of said bottles, but below the path of 75 movement of said transverse bars to stop the bottles in registering position with said filling means, and means for operating said arresting devices at intervals.

37. In apparatus of the class described, 80 the combination with a frame, of a liquid receptacle mounted thereon, bottle filling mechanism connected with the liquid receptacle, bottle capping mechanism mounted on the frame, intermittently operated 85 means arranged to move bottles from said filling mechanism to said capping mechanism, centering devices arranged to engage with mouths of bottles carried by said advancing means at predetermined intervals, stop devices arranged to engage with the bottles at their lower portions at predetermined intervals, and means for operating 90 said centering devices and said stop devices.

38. In apparatus of the class described, 95 the combination with a frame, of a liquid receptacle mounted thereon, a bottle filling mechanism connected with said receptacle, a capping mechanism mounted on said frame, an intermittently operated conveyer 100 for moving bottles from said filling mechanism to said capping mechanism, means for adjusting said conveyer toward and from said filling mechanism and said capping 105 mechanism, centering devices supported by the frame and arranged to engage with the mouths of bottles carried by the conveyer, stop devices adjustable with said conveyer toward and from the filling mechanism and the capping mechanism and arranged to engage the bottles near their bottom portions, and means for operating the stop devices at 110 intervals.

39. In a bottle filling and capping mechanism, the combination of a step by step bottle moving means, a bottle filling mechanism, a bottle capping mechanism, automatically operated stops engaging the bottles for limiting the forward movement 115 thereof relative to the filling and capping mechanisms, and devices for engaging the mouths of the bottles to center them relative to one of said mechanisms.

40. In a machine of the character de- 120

130

scribed, the combination of a frame, a bottle advancing means adapted to carry one or more longitudinal series of bottles, mechanism supported by said frame for supplying caps to the bottles, mechanism for filling the bottles, power mechanism, power transmitting devices for operating the bottle filling mechanism, devices connected with said power transmitting devices for operating 10 the cap supplying mechanism, means for adjusting the advancing means for the bottles bodily toward and from the filling mechanism and the cap supplying mechanism, and adjustable connections between 15 the power mechanism and the said bottle advancing means for operating the latter.

41. In mechanism of the class described, the combination of a frame, a liquid holder, mechanism connected with said holder for filling a plurality of bottles simultaneously, said mechanism including a plurality of ducts arranged in a row, each duct having a valve seat and a valve therefor, devices for feeding and positioning a plurality of 20 bottle caps in a row, means for advancing rows of bottles step by step and simultaneously positioning a row of bottles at the filling station with the mouth of each bottle in the row in alinement with one 25 of said filling ducts, and another row of bottles at the capping station with the mouth of each bottle in the row in alinement with one of said cap feeding and positioning devices, co-acting means for opening and closing said valves substantially 30 simultaneously and for actuating said cap feeding and positioning devices, means for raising and lowering the bottle advancing 35 means relative to said filling ducts and cap feeding and positioning devices, and means for varying the period of time that the said 40 valves are open.

42. In a machine of the class described, the combination of a receptacle for a liquid, 45 a bottle conveyer, devices for supplying and controlling the flow of the liquid from the said receptacle to bottles carried by the bottle conveyer, bottle capping devices for placing caps on the bottles, means for supplying a sealing material to the caps after 50 they have been positioned on the bottles, power mechanism, and connections between the power mechanism and the liquid control devices, the cap-positioning devices, 55 and the sealing material-supply means for automatically controlling the filling, capping and sealing of the bottles.

43. In apparatus of the character described, the combination of a frame, a conveyer mechanism, bottle filling mechanism having a cross head, bottle capping mechanism having a cross head, power mechanism, a lever operatively connected at one end with said power mechanism and arranged to engage the cross head of the fill-

ing mechanism at its opposite end to move the cross head in one direction, a second lever pivoted to said frame and arranged to engage with and operate the cross head of the capping mechanism, and a connection 70 between said levers whereby the second lever is operated by the first-mentioned lever.

44. In a bottling machine, the combination with the frame, of a driving shaft, a supply tank, filling tubes opening into said 75 tank, reciprocating sleeves slidably mounted upon said tubes, springs for said sleeves, valves situated in said sleeves and provided with tubular stems projecting axially through said tubes, a cross-head attached to 80 said stems, and adjustable means for reciprocating said cross-head.

45. In a bottle filling mechanism, the combination of a reservoir, a liquid tube connected thereto and provided with a movable 35 section adapted to engage a bottle mouth, a valve and a stem therefor arranged to support said movable section, means for moving said valve stem relative to said reservoir, and means tending to maintain said movable 90 section in engagement with said valve during movement of its stem but permitting said section to move relative to said valve.

46. In a bottle filling mechanism, the combination of a reservoir having discharge 95 ducts, a member provided with a valve seat movably connected with each of said ducts, a series of rods each carrying a valve and adapted to support one of the valve seat members at its lower end, each of said valve 100 seat members being arranged to conduct the liquid from the adjacent duct to the mouth of the bottle, means tending to hold each said member in engagement with the adjacent valve, and means for reciprocating said 105 rods relative to said reservoir.

47. In a bottle filling mechanism, the combination of a reservoir having discharge ducts, a member provided with a valve seat movably connected with each of said ducts, 110 a series of rods each carrying a valve and adapted to support one of the valve seat members at its lower end, each of said valve seat members being arranged to conduct the liquid from the adjacent duct to the mouth 115 of a bottle, a spring interposed between each valve seat member and the adjacent rod and tending to hold each said member in engagement with the adjacent valve, and means for reciprocating said rods relative 120 to said reservoir.

48. The combination in a bottle filling machine of a supporting structure; a tank thereon; a filling tube mounted in the bottom of the tank and consisting of two telescopic sections; a bottle engaging member on one of the sections; means normally tending to move the sections relatively to each other; a valve normally closing the lower end of one of the sections; an operating rod 125

for the valve consisting of a pipe extending through the filling tube; a member to which the upper end of said rod is connected; and means engaging said member for operating said valve through the medium of said pipe.

In testimony whereof I affix my signature in presence of two witnesses.

JOHN C. MILLER.

Witnesses:

J. H. MILLER,
C. GEIDLINGER.

It is hereby certified that in Letters Patent No. 1,225,349, granted May 8, 1917, upon the application of John C. Miller, of Canton, Ohio, for an improvement in "Apparatus for Filling and Capping Bottles," errors appear in the printed specification requiring correction as follows: Page 6, after line 77 insert the paragraph:

No claim is made herein to the disclosed subjects-matter relating to the mechanism for capping bottles and mechanism for handling bottles, the inventions therein being claimed by me in divisional applications Ser. Nos. 162,596 and 162,597, respectively, filed April 16, 1917.

page 9, lines 35-36, claim 24, for the compound word "cross-heads" read *cross-head*; same page, line 94, claim 29, for the word "mechanism" read *mechanisms*; and that the said Letters Patent should be read with these corrections therein that the same may conform to the record of the case in the Patent Office.

Signed and sealed this 26th day of June, A. D., 1917.

[SEAL.]

Cl. 226—28.

R. F. WHITEHEAD,

Acting Commissioner of Patents.
